UNITED STATES PATENT OFFICE.

OSWALD S. PULLIAM, OF PITTSBURGH, PENNSYLVANIA, ASSIGNEE, BY MESNE ASSIGNMENTS, TO DOUBLE BODY BOLSTER COMPANY, OF ST. LOUIS, MISSOURI, A CORPORATION OF NEW JERSEY.

UNDERFRAME FOR CARS.

1,106,110.

Specification of Letters Patent. Patented Aug. 4, 1914.

Application filed July 17, 1909. Serial No. 506,241.

To all whom it may concern:

Be it known that I, OSWALD S. PULLIAM, a resident of Pittsburgh, in the county of Allegheny and State of Pennsylvania, have 5 invented certain new and useful Improvements in Underframes for Cars, of which the following is a specification.

An object of the present invention is to provide a new and improved steel underframe for cars, locomotive tenders, and the like, in which the principle of the cantaliver is applied.

A further object of the present invention is the provision of an integral casting or 15 portion comprising a body-bolster, which casting is adapted to extend for quite a distance forwardly and rearwardly of the truck-bolster of a truck, and may in addition to the body-bolster comprise an end-sill and the entire end-portions of the underframe.

A still further object of this invention is the provision of a beam or center-sill of cantaliver construction that may be employed as a portion of the underframe of a car.

In the accompanying drawings, which illustrate applications of my invention, Fig. 1, is a perspective view of a car-body 30 underframe embodying my invention, with the connecting or middle section partly broken away; Fig. 2, a part side elevational and a part sectional view of the form of Fig. 1; Fig. 3, an end-view; Fig. 4 an inverted perspective view of one of the end sections or portions; Fig. 5, a broken perspective view showing a modified middle or connecting section; Fig. 6, a perspective view of a modified form of a car-body underframe, constructed in accordance with my invention; Fig. 7, a central longitudinal sectional view of the form of Fig. 6; Fig. 8 a sectional view taken on line VIII-VIII of Fig. 7; Fig. 9, an inverted perspective 45 view of one of the end sections shown in the form of Fig. 6; Fig. 10, a part side elevational and a part sectional view of a beam constructed in accordance with my invention; and Fig. 11, a part plan and a part 50 sectional view of the beam shown by Fig. 10.

This invention may be employed in the construction of various kinds of cars, tenders, and the like; in the drawings, however, I have particularly shown embodiments of

my invention as utilized in the construction 55 of steel underframes for cars in which the principle of the cantaliver is applied.

In the form of my invention as shown by Fig. 1, 2 and 3 designate end-portions or sections each formed with a body-bolster 4, 60 side-sills 5, and end-sills 6, central members 7, extending forwardly and rearwardly of the body-bolster and a floor 8. End-portions or sections 2 and 3 are designed to be supported by their respective bolsters upon 65 truck-bolsters, not shown, and to extend from both sides of the truck-bolsters for a considerable and substantially the same distance, thereby producing a substantially balanced structure having its bearing on the 70 center plate of the truck-bolster of the car. The inner-ends of the sections 2 and 3 sustain a middle section 9, which latter connects the two end-portions.

In the form of Fig. 5 I have shown several 75 connecting bars 9^a in place of the integral structure 9 shown by Fig. 1.

Fig. 6, shows a modified form of end-sections from those of Fig. 1, and somewhat different means for connecting said sections, 80 but this form of my invention, it will of course be noted, retains the principle of the cantaliver.

In the form of Fig. 10, I show a beam 85 designed to be used for a center sill of a car-underframe in which the principle of the cantaliver is also applied. In this construction 2^b and 3^b designate the end-portions and 9^b the middle or connecting member.

As illustrated, I have shown the body-bolsters formed with center-bearings 10 and side-bearings 11, but these parts may be made separate if preferred.

As shown by Fig. 1, the end-portions 2 and 3 may have formed integral therewith 95 car side-walls 12 and an end-wall 13. As shown, these walls are not of great height, but it is evident that they may be extended to a much greater height than shown.

What I claim is:

1. A metal underframe for cars and the like, of cantaliver construction comprising two substantially balanced end portions, each formed of an integral casting comprising a body bolster, an end sill, an inner 105 transversely extending end member, and sections of side sills, said end portions adapted to extend forwardly and rear-

wardly of the truck bolsters, and means connecting the inner transversely extending end members of said end portions.

2. In an underframe for cars and the like, an end portion formed with a floor member having upwardly projecting flanges a body bolster, an end sill, and sections of side sills, said end portion being adapted to be substantially balanced on the center plate of a truck bolster and to extend approximately equal distances to the front and rear of said bolster.

3. A steel underframe for cars and the like of cantaliver construction comprising two end-ports, each comprising an integral structure formed with a body-bolster, a transversely disposed straight inner end sill, sections of side sills and designed to extend forwardly and rearwardly of the truck bolster and be supported thereby, and means for rigidly connecting said end portions, which connecting means is fixed to the transversely disposed inner end sills of the end portions.

4. A steel underframe for cars and the like comprising two end-ports each formed with a body-bolster, a straight transversely disposed inner end-sill, a section of a side-sill, and a floor member each adapted to be substantially balanced on the center plate of the truck-bolster, and means attached to the inner end sills.

5. A steel underframe for cars and the like comprising two end-ports each formed with a floor-member, a body-bolster, axle bearings thereon, a straight transversely disposed end sill, and a section of a side sill, said portions each adapted to be substantially balanced on the center plate of the truck-bolster, and means for rigidly connecting said portions.

6. A steel underframe for cars and the like of cantaliver construction, comprising two end portions each formed with a body bolster and a transversely extending member to the rear of the body bolster, said end portions each adapted to be substantially balanced on the center plate of a truck bolster, and means connecting the trans-

versely extending members of said end portions.

7. The combination of a tender frame made in transverse sections each section being rectangular in shape; the parting line between the sections being straight and extending from one side of the frame to the other; with means for securing the several sections together.

8. In a sectional underframe for cars, an integrally formed end portion comprising a body bolster, an end sill, a straight transversely disposed inner end member, side sill sections between the ends of the end sill and the inner end member, and sill members between the body bolster and the end sill and the inner end member.

9. In a sectional underframe for cars, an end portion comprising a body bolster, side sill members integral with the ends of said body bolster, transversely disposed sill members integral with and arranged between the ends of the side sill members, and integral webs between the body bolster and the transversely disposed sill members.

10. In a sectional underframe for cars, an end portion comprising a body bolster, side sill members integral with the ends thereof, a straight transversely disposed sill member integral with the inner ends of said side sill members, and an integral web between the central portion of the body bolster and the transversely disposed sill member.

11. In an underframe for cars, two end portions each formed in a single piece and comprising a body bolster, side sill members integral with the ends thereof, a straight transversely disposed sill member connecting the inner ends of said side sill members, and means attached to the transversely disposed sill members for rigidly connecting the two end portions.

In testimony whereof I affix my signature in presence of two witnesses.

OSWALD S. PULLIAM.
